UNITED STATES PATENT OFFICE.

PETER R. WARREN, OF LOWELL, MASSACHUSETTS.

BOX.

975,911.

Specification of Letters Patent. Patented Nov. 15, 1910.

Application filed June 14, 1909. Serial No. 501,959.

To all whom it may concern:

Be it known that I, PETER R. WARREN, a citizen of the United States, residing at Lowell, county of Middlesex, State of Massachusetts, have invented a certain new and useful Improvement in Boxes, of which the following is a specification, reference being had therein to the accompanying drawings.

My invention has for its object a box provided with a sight opening through which the contents of the box is visible and which is closed by a sheet of transparent material such as gelatin, transparent celluloid, mica or the like. These boxes are particularly adapted for use in cases where it is desired that the prospective purchaser shall have the opportunity of seeing the goods, but where it is desired to protect the goods from dirt and moisture. The package embodying my invention is particularly adapted for use in connection with the sale of confectionery, lozenges, and medicines which it is desired shall be visible to the purchaser but shall also be protected so that the purchaser cannot injure the goods by handling them. My improved box is, however, not limited to these uses. In boxes of this kind as heretofore constructed, great difficulty has been experienced because of the tendency of the transparent material, particularly where gelatin is used, to curl, which makes it difficult to keep the transparent material in place while the contents of the box is being put in place and also because the contents of the box is not properly protected if the transparent material is allowed to curl as it then draws away from the remainder of the box and leaves an opening through which dust may enter. The box embodying my present invention does away with these difficulties. It is so constructed that the transparent material may be readily and securely put in place, and when once put in place, is held so that it cannot become displaced without destroying the remainder of the box. As the transparent material lies between two of the layers of card board forming the box, it cannot curl at all and consequently the box is always tight and no dust can enter. A box embodying my invention is no more expensive to construct than are the boxes which have heretofore been ordinarily employed for these purposes.

While I have shown in the accompanying drawings my invention embodied in a so-called folding box because that is the form

in which I have put my invention into actual practice, it is obvious that it may be embodied in boxes of other forms, such for instance as the well known solid box. 60

The invention will be fully understood from the following description taken in connection with the accompanying drawings, and the novel features are pointed out and clearly defined in the claims at the close 65 of the specification.

In the drawings,—Figure 1 is a plan view of a blank which, when folded and supplied with a sheet of transparent material, forms a box embodying my present invention. 70 Fig. 2 shows the sheet of transparent material. Fig. 3 is a perspective view showing the blank shown in Fig. 1 partly folded and the sheet of transparent material shown in Fig. 2 in place. Fig. 4 is a transverse section of the finished box embodying my invention. 75

Referring to the drawings, there is shown in Fig. 1 the blank from which a folding box embodying my invention is constructed. This blank consists of a bottom portion A, an inside top portion B and an outside top portion C as well as such ends D and tucks E as may be required. In the outside top portion is cut a sight opening F 85 of the desired size and in the inside top portion is cut another sight opening G which is of a size slightly greater than that of the sight opening F so that when the two parts are in registration with each other, the inner layer of card board B will not be revealed to a person looking through the sight opening F. The relative position of the two sight openings will plainly be seen in Fig. 4. 90

In one or the other of the portions of the 95 blank containing the two sight openings are cut slits H, H, of curved shape into which the edges of the sheet of transparent material K, see Fig. 2, are inserted as seen in Fig. 3. These slits may be of any desired 100 form or arrangement and may or may not form tabs as shown in Fig. 1. I prefer to cut them in the inside-top portion B as shown in Fig. 1, as when thus placed, they are not visible when the box is completed. 105 After the transparent material has been inserted into the slits H, the side portions L and M are glued together and the side portions N and O are glued together. When this is done, the sheet of transparent material 110 will be seen to be held securely between the two layers of card board and

therefore to be held flat so that it cannot curl, bend or fall out. It will also be seen that it cannot be slid out endwise being held from movement in this direction by the slits

5 H. H. With boxes as thus constructed no difficulty is experienced on account of the tendency of the transparent material to curl or get out of place and the contents of the box are as completely protected from dust

10 as if contained in a box which had no sight opening.

What I claim is:

1. The improved folding box comprising a blank of card board, having two portions 15 thereof lying the one against the other, each of said portions having a sight opening therein in registration with each other, one of said two portions of the blank having slits therein and a sheet of transparent material between said two portions of the blank having some of its edges located in said slits.
2. The improved folding box comprising a blank of card board, having two portions 25 thereof lying the one against the other and secured together, each of said two portions having a sight opening therein in registration with each other, the sight opening in the outer of the said two portions being the
- 30 smaller, one of said two portions of the blank having slits therein and a sheet of transparent material between said two portions of the blank having some of its edges in said slits.
- 35 3. A pasteboard box having a display

opening in one wall and an apertured fold of the box blank lying inside of and adjacent to said wall with said opening and aperture in register, said fold along an edge having a flap resting along its edge on the box wall opposite that equipped with said opening and acting to retain said fold in substantially parallel relation with and in juxtaposition to said first wall, whereby a sheet of transparent medium may be interposed between said fold and wall and be held in proper relation to the opening of the latter to constitute a window said medium being maintained in such position by the wall and fold on opposite sides thereof.

40

4. A pasteboard box having a display opening in one wall and an apertured fold of the box blank lying inside of and adjacent to said wall with said opening and said aperture in register, said fold along an edge 45 having a flap lying adjacent the side wall of the box and acting to retain said fold in substantially parallel relation with and in juxtaposition to said first wall whereby a sheet of transparent medium may be interposed between said fold and wall and be held in proper relation to the opening of the latter to constitute a window.

50

In testimony whereof I affix my signature, in presence of two witnesses.

PETER R. WARREN.
